UNITED STATES PATENT OFFICE.

FREDERICK A. FRERICHS, OF PHILADELPHIA, PENNSYLVANIA, ASSIGNOR TO THE
HORN & BRANNEN MANUFACTURING CO. INC., OF PHILADELPHIA, PENNSYLVANIA, A CORPORATION OF PENNSYLVANIA.

ELECTRIC-SOCKET SUPPORT AND HOUSING.

Application filed April 23, 1926. Serial No. 104,135.

My invention relates to electric lighting fixtures and has for its object to provide a small, neat housing which can be used with standard fixture stems and which will furnish unusual strength for the connection.

My invention has for its further object to furnish a clear pathway for the electric conductors or wires, which will be free of obstructions, such as tight or twisted corners—which in the ordinary construction tend to cause abrasion of the insulation on the wires, thus causing short circuits with their attendant dangers.

My means of accomplishing the foregoing object may be more readily understood by having reference to the accompanying drawings, in which—

Fig. 1 is a vertical, sectional view of my improvement; and

Fig. 2 is a side elevation of the same.

Similar reference numerals refer to similar parts throughout the entire description.

As shown in the drawings, the fixture stem 1 extends from the fixture (not shown), and has mounted at its outer end 2, my improved housing 3. This housing is formed of a cylindrical tube in which is located a standard socket shell 4 which is provided with the usual standard sleeve 5 formed of suitable insulating material. Within the tube 3, at the point of entrance of the stem 1, I mount a section of tubing 6 which has a very thick or heavy wall, which is provided with a threaded opening 7, into which the threads on the end of the stem 1 may be screwed.

To those skilled in the art, it will be apparent from the foregoing description that this construction provides a thickness for the support of the housing, which is not to be found in the ordinary housings, and hence possesses unusual strength at this point.

The lower end 8 of the tube 3 is closed by a disc 9 having a central aperture 10 which forms a convenient pull in box for the electric wires (A) and in which is mounted an upwardly extending stem 11 formed on a plate 12 and fitting the threaded portion of the hickey 13 of the socket shell 4. The rotation of the socket 4 is prevented by means of a small screw 14 which passes through a threaded hole 15 and extends into a hole 16 formed in the disc 9, though any other suitable means for this purpose may

be employed. The plate 12 is provided with a downwardly depending boss which is provided with a central opening 17 which is threaded to provide for a threaded bolt which extends upwardly from a cap 18, the periphery of which engages an annulus 19 which engages a circumferential corrugation 20, which prevents its upward movement.

At the upper end of the tube 3 is mounted an ornamental annulus 21 which telescopes the tube 3 and rests against another circumferential corrugation 22. This may, if desired, be used as a rest for the shade. It will be obvious that the construction thus described will present an appearance closely resembling the fount of one of the old-fashioned oil lamps which are so popular at the present time. It will be seen that I have entirely done away with the external shell of the socket, thus materially reducing the size of the housing.

My method of assembling the fixture is as follows: The electric wires A are first connected to the terminal screws of the socket 4; the other end of the wires are then passed through the housing and then through the stem 1. The socket is then inserted in the housing 3 until the hickey 13 reaches the plate 12. The threaded stem 11, on the plate 12, is then screwed into the threaded portion of the hickey 13, the small screw 14, preventing its being unscrewed. From the foregoing it will be apparent that I entirely avoid the usual danger of short-circuiting the wires when the wires are necessarily twisted in screwing the socket into its position.

Having thus described my invention, what I regard as new and desire to secure by Letters Patent of the United States is:

1. A fixture stem, a standard electric socket shell, a hickey secured to the shell, a housing in which said shell is mounted, said housing having a thickened wall where the stem joins it, an apertured disc which closes the lower end of said housing, a plate secured to the disc, a threaded stem thereon which enters said aperture, said stem fitting the threaded part of the hickey of said socket shell, and means to prevent the rotation of said disc carrying the shell.

2. A fixture stem, a standard electric socket shell, a hickey secured to the shell, a housing in which said shell is mounted, said

housing having a thickened wall where the stem joins it, an apertured disc which closes the lower end of said housing, a plate, a threaded stem thereon which enters said aperture, said stem fitting the threaded part of the hickey of said socket shell, a boss on the lower side of said plate, a cap having a bolt which is threaded into said boss and a screw in said plate which engages said disc, and prevents the rotation of the plate.

3. A fixture stem, a standard electric socket shell, a hickey secured to the shell, a housing in which said shell is mounted, said housing having a thickened wall where the stem joins it, an apertured disc which closes

the lower end of said housing, a plate secured to the disc, a threaded stem thereon which enters said aperture, said stem fitting a threaded part of the hickey of said socket shell, a boss on the lower side of said plate, a cap having a bolt which is threaded into said boss and a screw in said plate which engages said disc, and prevents the rotation of the plate, an annulus on said housing engaged by said cap, and means formed on said housing to prevent the longitudinal movement of said annulus beyond a predetermined point.

FREDERICK A. FRERICHS.
